BUCKING BAR FOR TUBULAR MEMBERS

Alfred H. Haberstump, Detroit, Mich., assignor
to The Murray Corporation of America, Detroit,
Mich., a corporation of Delaware

Application December 17, 1942, Serial No. 469,321

9 Claims. (Cl. 78—53.5)

This invention relates to bucking bars and particularly to a new and novel bucking bar employed for bucking a rivet on the inside of tubular elements.

When the rivets which extend through the wall of a tubular element of small diameter are to be bucked, difficulty has been experienced in positioning a dolly within the element in position to engage and buck the rivet. Especially is this true when the rivets have their heads on the outside of the tube and are driven from the outside in the manner employed in the aircraft industry. While some types of bucking bars have been heretofore constructed to back the rivets which extend through a tubular wall, these, as far as applicant knows, are not entirely successful because of the fact that the same reaction is not obtained at all points throughout the length of the bar.

Following the teaching of the copending application to A. H. Haberstump, Serial No. 440,837, filed April 28, 1942, and assigned to the assignee of the present invention, the bucking bar of the present invention is supported in parallelogram relation to the base so that the same reaction is obtained at all points throughout the bar length. The bar may span any number of rivets and the entire number is swaged without the necessity of moving the bar from one rivet to another as the same reaction will obtain at all points along the bar. This is necessary when employing a timing device on the percussion hammer such as that illustrated and described in the copending application of A. H. Haberstump, Serial No. 439,115, filed April 15, 1942, and assigned to the assignee of the present invention. This timing device controls the number of strokes struck by the hammer during the cycle and when bucked in the same manner identical bucktails will be swaged on the ends of all of the rivets being driven. If the bar would react differently at points throughout its length, it will be readily apparent that different swaging operations would be performed on the rivets when struck the same number of times and the bucktails produced would not all be the same.

The bucking bar embodies a base element having links pivoted thereon in parallel relation. The bucking bar is a solid element having recesses for receiving the links so that the bar is maintained at all times in parallel relation to the base element. A piston is aligned with the bar having an arcuate end portion which abuts against the bar end and is the means for moving the bar arcuately on the links upwardly into

engagement with the inner wall of the tube. Only sufficient pressure is employed when raising the bar so that it may be deflected by a rivet when forced downwardly by the operator when applying the riveting hammer to the rivet head. As the hammer operates, the impact is applied through the rivets to the bar which swages the end as the bar is maintained against the rivet by the application of the force on one of its ends. The cylinder is connected to a flexible conductor by which the bucking bar is advanced along the wall. Air is introduced into the cylinder through the conductor to move the piston outwardly for moving and holding the bucking bar against the wall of the tube or the rivet ends. When the rivet is forced downwardly to have its head engage the surface of the outer element to be riveted, the bar is deflected against the piston which is forced back against the pressure in the cylinder.

Accordingly, the main objects of this invention are: to provide a bucking bar for a tube having a base element and a bucking element in parallel relation to each other interconnected by parallel links which are in pivotal relation therewith and manipulate the bar on the links with a piston in aligned relation with the bar; to form a bucking bar from a base element which is a channel-shaped stamping having bosses for pivoting links on which a solid bucking bar is pivoted and controlled by a piston and cylinder mounted on the end of the base to which pressure is delivered by a flexible conductor by which the bucking bar is manipulated in a tube to be riveted; to construct a compact bucking bar from a channel element and a T-shaped bar which are interconnected by a pair of links to produce parallelogram relationship theretwixt and provide a flexible conductor at the end of the bar for applying pressure thereto; and in general to provide a compact bucking bar which is insertable within a tubular element of small diameter, which is simple in construction, positive in operation, and economical of manufacture.

Other objects and features of novelty of this invention will be specifically pointed out or will become apparent when referring, for a better understanding of this invention, to the following description taken in conjunction with the accompanying drawing, wherein:

Figure 1 is a view in elevation of a collapsed bucking bar mounted within a tubular element, illustrated in section which embodies features of this invention;

Figure 2 is a view of the structure illustrated

in Figure 1, with parts in section and with the bar in raised operating position;

Figure 3 is a sectional view of the bucking bar illustrated in Figure 1, taken on the line 3—3 thereof; and

Figure 4 is a sectional view of the structure illustrated in Figure 1, taken on the line 4—4 thereof.

The bucking bar embodies a base element 10 which is of channel section having bosses 11 welded or otherwise secured near opposite ends thereof. The forward end of the bar is arched upwardly at 12 while the rear end is extended at 13 and flanged upwardly at 14 to form a rear wall having an aperture 15 therethrough. A pair of links 16 are pivoted at one end to the bosses 11 by the pins 17 while the opposite ends are pivoted by the pin 18 to the bucking element 19. The element 19 is provided with recesses 21 for receiving the links and cutaway portions 22 and 23 for receiving the bosses 11.

The bucking element 19, as illustrated in Figs. 3 and 4, is T-shaped in section having an enlarged head 24 which engages the rivets. The element 19 is retained at all times parallel to the base element 10 because of its support on the links 16 and will produce the same reaction in the central as well as the overhanging end portion thereof. The same reaction is obtained for swaging the bucktails on the rivets at all points throughout the bar length as when the hammer is operated on a predetermined time cycle assurance will be had that all of the bucktails formed on the swaged rivets will be exactly of the same diameter and thickness.

For applying resilient pressure to the bucking bar while retaining the bar compact so as to be insertable in a tubular element of small diameter, a cylinder 25 having a threaded stem 26 is mounted in the extending end portion 13 of the base element 10 with the threaded stem extending through the aperture 15 and secured in position by a nut 26. A hose connector 28 is threaded within the stem 26 and a hose 29 is secured thereto by suitable means, herein illustrated as by a clamp 31. A piston 32 extends within the cylinder 26 and is sealed thereto by a sealing cup 33 of conventional form which is retained in position by a washer 34 and a screw 35. The outer end of the piston 32 has an arcuate head 36 which provides point engagement with the end of the bucking element 19 which permits the bucking element to move across the head without material resistance. It is to be understood that while the piston herein illustrated is to be operated by fluid pressure, that a spring could be employed within the cylinder 25 for operating the piston, the tension on which may be applied by the movement of a wire or rod through the hose 29.

In Figure 1, the bucking bar is illustrated with the piston retracted within the cylinder 25 and the bucking element 19 moved downwardly onto the base element 10. In this position, the bar is readily inserted within the tubular element, such as 37, to which an element 38 is to be riveted. After the bar has been inserted sufficiently to engage a plurality of the rivets, air is applied to the cylinder 25 through the hose 29 to move the piston to the left, as viewed in the figure, to thereby move the bucking element 19 upwardly on the links 16 into engagement with the inner surface of the tubular element or to the bucktail of rivets which have already been driven.

A rivet, such as 39, is inserted in an aperture through the elements 38 and 37 and the driving

dolly 41 of a riveting hammer is placed against the head of the rivet forced downwardly to push the head of the rivet into engagement with the outer surface of the element 38. This deflects the bucking element 19 which reacts against the piston 32 to move the piston against the pressure of air within the cylinder 25. As the driving hammer is operated, the impact applied to the rivets causes the end thereof to become swaged as the bucking bar is constantly urged against the end thereof, so that after a predetermined time cycle a bucktail 42, such as that illustrated in Fig. 2, is formed on the end of the rivet.

All of the rivets which can be spanned by the bucking element 19 are driven in this manner and like bucktails 42 will be formed on all of the ends thereof because of the exact reaction to the bucking operation by the bucking bar at all points along its length. Thereafter, pressure is removed from the cylinder 25 permitting the piston 32 to retract as the bucking element 19 moves downwardly upon the base element 10. The bucking bar may be moved further within the tube thereafter to span an additional group of the rivets to be swaged. Air will again be applied through the hose 29 into the cylinder 25 to again advance the piston and the bucking element 19 into engagement with the inner surface of the tubular element 37. By marking the hose 29, the position of the bucking bar 10 on the inside of the tube can readily be ascertained and the bucking bar can be accurately located in this manner.

What is claimed is:

1. A bucking bar comprising, a base element, a pair of links pivoted to said base element, a bucking element pivoted on the end of the links, a cylinder supported by the base element in aligned relation to said bucking element, and a piston in said cylinder in abutted engagement with one end of the bucking element.

2. A bucking bar comprising, a base element, a pair of links pivoted to said base element, a bucking element pivoted on the end of the links, a cylinder supported by the base element in aligned relation to said bucking element, a piston in said cylinder contacting the bucking element, and a flexible hose connected to the cylinder.

3. A bucking bar for a hollow tube including, a base element of channel section, bosses provided within the channel element, links pivoted to said bosses, a bucking element supported within the channel on the pair of links, a cylinder supported by the channel element beyond one end of the bucking element, and a piston within said cylinder movable into engagement with the end of said bucking element.

4. A bucking bar for a hollow tube including, a base element of channel section, bosses provided within the channel element, links pivoted to said bosses, a bucking element supported within the channel on the pair of links, a cylinder supported by the channel element beyond one end of the bucking element, a piston within said cylinder movable into engagement with the end of said bucking element, and a flexible fluid conductor secured to the end of the cylinder for conducting pressure thereto and for manipulating the bucking bar within the hollow tube.

5. A bucking bar for a tubular element embodying a base element comprising a stamping of channel section having an upwardly arched front end portion and an upwardly extending rear portion having an aperture, a cylinder in the rear portion having a hollow extending stem projecting through said aperture and secured

thereto, a T-shaped bucking bar having recessed portions, a pair of links each pivoted within a recess, pivots for interconnecting the opposite ends of the links to the base element, and a piston within said cylinder for operating the T-shaped bucking element.

6. A bucking bar for a tubular element embodying a base element comprising a stamping of channel section having an upwardly arched front end portion and an upwardly extending rear portion having an aperture, a cylinder in the rear portion having a hollow extending stem projecting through said aperture and secured thereto, a T-shaped bucking bar having recessed portions, a pair of links each pivoted within a recess, and a piston within said cylinder having an arcuate end which abuts against the end of the bucking element.

7. A bucking bar for a tubular element embodying a base element comprising a stamping of channel section having an upwardly arched front end portion and an upwardly extending rear portion having an aperture, a cylinder in the rear portion having a hollow extending stem projecting through said aperture and secured thereto, a T-shaped bucking bar having recessed portions, a pair of links each provided within a recess, a piston within said cylinder having an arcuate end which abuts against the end of the

bucking element, and a flexible conductor secured to the end of the cylinder for conducting air to the piston and for manipulating the bucking bar within the hollow tubular element.

8. A bucking bar embodying a base element which is a channel-shaped stamping, spaced links supported on said base element, a bucking element pivoted on said links to provide a parallelogram relationship between the bucking element and the base element, and resilient means supported at one end of the base element in alignment with said bucking element for urging the bucking element upwardly on the links and provide a predetermined pressure thereto.

9. A bucking bar embodying a base element which is a channel-shaped stamping, spaced links supported in said base element, a bucking element pivoted on said links to provide a parallelogram relationship between the bucking element and the base element, resilient means supported at one end of the base element in alignment with said bucking element for urging the bucking element upwardly on the links and provide a predetermined pressure thereto, and a flexible extension on said bucking bar through which the pressure on said bucking element is adjusted.

ALFRED H. HABERSTUMP.
